Primary Examiner — Patricia A Palasik(74) *Attorney, Agent, or Firm* — Birch, Stewart, Kolasch & Birch, LLP(57) **CLAIM**

The ornamental design for a scroll member of a scroll fluid machine, as shown and described.

DESCRIPTION

FIG. 1 is a front view of a scroll member of a scroll fluid machine showing our new design;

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a perspective view thereof in the direction of arrow 7 of FIG. 3;

FIG. 8 is a perspective view thereof in the direction of arrow 8 of FIG. 3;

FIG. 9 is a sectional view along line 9-9 of FIG. 1; and,
FIG. 10 is a sectional view along line 10-10 of FIG. 3.

The broken lines in the drawings depict portions of the scroll member of scroll fluid machine which form no part of the claimed design.
